UNITED STATES PATENT OFFICE

2,477,100

FEED MECHANISM FOR FASTENER SETTING MACHINES

Jacob P. Treciokas, Oakville, Conn., assignor to Scovill Manufacturing Company, Waterbury, Conn., a corporation of Connecticut

Application March 22, 1946, Serial No. 656,278

19 Claims. (Cl. 218—6)

1

This invention relates to machines for setting or assembling buttons or other fastener elements upon a supporting structure, such as a garment or a fabric or other support of any type or kind. More particularly, the present invention deals with the method and mechanism for actuating the fastener feed or delivery members of the machine in a manner to eliminate and dispense with hammer-like noise of machines of the kind under consideration. Further, the invention deals in the provision of a novel pick-up and delivery element for delivering fastener devices to position for advancement in the machine by the feed, slide or finger employed therefor. Still more particularly, the invention comprises a lever mechanism having a free action to compensate for jamming or blocked movement of the feed fingers or slides employed to feed or deliver the fastening devices to operative position in the machine. The novel features of the invention will be best understood from the following descriptions when taken together with the accompanying drawings, in which certain embodiments of the invention are disclosed, and in which the separate parts are designated by suitable reference characters in each of the views, and in which:

Fig. 1 is a side and sectional view of part of a machine made according to my invention, showing the lever mechanism in advanced position in full lines and in retarded position in dot-dash lines, parts of the construction being broken away.

Fig. 2 is a sectional plan view substantially on the line 2—2 of Fig. 1, on an enlarged scale, and with parts broken away.

Fig. 3 is a view similar to Fig. 2, omitting part of the construction and showing the parts in a different position.

Fig. 4 is a front view of the machine with parts of the construction omitted, the view being enlarged with respect to the showing in Fig. 1; and

Fig. 5 is a section on the broken line 5—5 of Fig. 3.

The machine forming the subject matter of this invention is of the general type and kind disclosed in the Warner Patent 1,575,596 of March 2, 1926, and also as disclosed in my prior application Ser. No. 542,925 filed June 30, 1944, now Patent Number 2,406,516, granted August 27, 1946.

As my present invention is concerned primarily with the feed or delivery of the fastener devices to fastener assemblage station, reference to the machine as a whole will be generally made and

2

only such parts of the machine as deal with my new conception will be dealt with specifically.

Considering Fig. 1 of the drawing, 10 represents the bed-plate of the machine arranged upon a suitable base or support 11. Extending upwardly from the plate 10 is a suitable frame 12 on the upper portion of which is pivoted, as seen at 13, an operating lever 14 for actuating the fastener setting mechanism of the machine, generally shown at 15, in Fig. 1 of the drawing.

At 16 is shown part of a hopper from which the button fastener devices, not shown, are fed downwardly through a guide track 17 to a position to be delivered by a delivery or feed finger or rod 18, as taught in my application above identified, which delivers the button devices one at a time beneath the setting plunger or securing mechanism 15.

The finger or rod 18 has a suitable guide 19 in the frame 12 of the machine and pivoted to the rear end of the finger 18 is a fork-shaped coupling 20. At 21 is shown the drive and cam shaft of the machine which operates a crank 22, having an adjustable link coupling 23 with the rear end of the lever 14, as at 24. Mounted for swinging movement upon the shaft 21 is an articulate type of bell crank comprising a long lever 25, and a shorter lever 26, the lever 26 being provided with a pin fixed thereto, as at 27, and the other lever 25 being provided with a circumferentially elongated slot 28 engaged by the pin 27 to provide relative movement of the levers 25—26 to the extent of the slot length. A spring 29 is coupled with the end portions of the levers 25 and 26 and serve to maintain these levers in a position approximately ninety-seven degrees from each other while permitting wider separation of the levers through the pin and slot construction. This free relative movement against the action of the spring 29 compensates for obstructions that might be engaged by the button feed finger 18 or the tack feed finger or slide 30, as will later more fully appear.

Pivoted to the free end portion of the short arm 26, as at 31, is a link 32, which is also pivoted to the main operating lever 14, as at 33. It will thus be seen that as the lever 14 is actuated through the crank 22 and link 23, the levers 26, 25 and 37 are also actuated in controlling forward and backward motions of the fingers 18—30 in the pick-up and feed of the button and tack to position at the securing or coupling station, identified, for example, as the position of the tack 34, as seen in Fig. 2 of the drawing, which would be a position directly beneath a button

arranged in the lower portion of the plunger mechanism 15. The lever 25 has a short downwardly extending arm 35 to which is pivoted an adjustable link 36, also pivoted to a lever 37, the latter being pivoted in the frame of the machine, as at 38. Pivoted to the upper end of the lever 37, as at 39, is a coupling link 40, the latter being also pivoted to the yoke coupling 20, as at 41, for the purpose of operating the feed finger 18.

The upper end of the lever 25 has a bearing portion 42, note Fig. 2, in which is rotatably mounted a block 43. Adjustably coupled with the block 43 is a coupling rod 44, as seen at 45, the forward end of the rod 44 being fork-shaped in form, as seen at 46, and pivoted to the fork end 46, as at 47, is a tack delivery or feed slide 48 having an upstanding rib the forward end of which includes the delivery finger 30. The forward end of the slide 48 proper has a curved recess 49 to seat upon the head 50 of the tack 34, as clearly seen at the left of Fig. 2 of the drawing.

By reason of the fact that the length of the lever 25 is greater than lever 37 from their respective pivots 21 and 38 to their upper free ends, and the relative differences in their lengths below said pivots, a greater feed is contributed to the finger 30 than to the finger 18. It will also be apparent that the stop position for the advance stroke of the feed fingers 18 and 30 are independently controlled by separate adjusting means. Specifically the finger 30 is adjusted as at 45 at the top of the lever 25, and the finger 18 is adjusted to predetermined position by the adjustable link 36 connected between the lower ends of levers 35 and 37.

Considering Figs. 2 and 3 of the drawing, at 51 I have shown the lower portion of a tack delivery chute into which tacks are fed by a hopper or other means, not shown, and this chute is disposed at right angles to the slide 48, and the suitable guides 52 and 53 provided for said slide, with the lower portion 51' of the chute arranged in horizontal alinement with the slide and guides, as will appear from a consideration of Figs. 4 and 5 of the drawing.

The upper portion of the end 51' of the chute is cut away, as seen at 54, note Fig. 2, to receive what I term a cut-off and carry element or lever 55. The element 55 may also be considered as a tack pick-up and delivery element. It comprises a substantially V-shaped lever pivoted, as seen at 56, and having a notch or recess 57 therein for engaging the tack prong 58, as seen at Figs. 3 and 5 of the drawing.

Coupled with the element 55, as at 59, is a spring 60, also secured to one of the guides, as at 61, which spring normally serves to maintain the element 55 in a retracted position shown in Fig. 3 of the drawing while permitting the element 55 to be moved into the delivery position shown in Fig. 2, at which position the slide 48, including the finger 30 thereof, picks up the tack and advances it to the assembly or securing station, as indicated by the tack 34 at the left of Fig. 2 of the drawing.

Attached to the underside of the cut-off and carrier element 55 is a roller 62 that is adapted to be engaged by the advancing feed finger 30 for operating said element 55. Cut-out portions 63 are provided in the adjacent faces of the guide blocks 52-53 for the purpose of clearance for the roller 62 when the element 55 is disposed in its opposite operating positions. A plate 64

forms the base for the guide channel 68 and upon which the slide 48 is adapted to operate. This plate 64 is supported upon a bracket 10' which in turn is supported upon the bed-plate 5 10 (see Fig. 1). Above the guide blocks 52-53 is a cover or retainer plate 66 for retaining the transfer element 55 in position.

Provision is made for a relatively wide biased channel 67 and also a narrower arcuate channel 10 70 in the guide block 52, the channel 67 serving as a clearance for the head of the tack or fastener element, and the channel 70 serving as a clearance for the tack shank when moved from the lower end of the chute, note Fig. 3, to the position in alinement with the channel 68 of the guides 52 and 53 and in front of the slide 48 and finger 30 thereon. As the slide 48 including the finger 30 thereon advances forwardly, the roller 62 is supported in the path of the raised finger 30 of the slide 48, in Fig. 3, and is then moved into the recess 63 and held in such recess by the raised portion of the slide 48 of which the finger 30 constitutes a part only. The finger 30 is retracted to clear the roller 62, at which time, the spring 60 returns the element 25 to the position shown in Fig. 3.

From the foregoing it will be apparent that the element 55 will pick-up only the lowermost tack in the chute, as in Fig. 3, and deliver it to the position in front of the slide 48. In this movement of the element, the rounded surface 69 on the element 55 holds the next successive tack in position, as in Fig. 2, ready to drop into the notch 57 when the element 55 is returned to the position of Fig. 3. It is to be noted that the arcuate surface 69 on the element 55 is struck as an arc with the pivot point 56 as a center so as to provide a uniform uninterrupted surface for supporting the foremost tack 34 in the end of the feed track 51, and therefore, will preclude the tack elements in said track 51 from being jumped backwardly in said track when the element 55 is quickly returned to its tack pick-up position, as seen in Fig. 3. In this manner, an assurance is had of the pick-up and delivery by the element 55 of a single tack from the track 51 into the channel 68 in line with the feed slide 48. It will be apparent that the channel 67 is in alinement with the lower end 51' of the chute 51, and this alinement is maintained by a suitable L-shaped bracket 71 which is secured to the bracket 10' as by screws 71', as is clearly seen in Fig. 5 of the drawing.

Returning now to Figs. 1 and 4 of the drawing, it will appear that on the shaft 21 is a cam 21' for moving a slide 72 downwardly, carrying a pair of pivoted jaws 73 to separate said jaws against the action of a spring 74 in the operation of setting or securing the fastener devices 60 to a suitable support. Coupled with the slide 72 is a link 75 which is pivoted to a lever 76, the latter being pivoted in the frame, as seen at 77, and carrying at its rear end a roller 78 operating upon the cam 21'. The forward end of the lever 76 has a hand portion 79 by means of which the jaws 73 may be separated by hand whenever desired. A spring 80 coupled with the frame and to the lever 76, note Fig. 1, holds the jaws 73 in closed position and the roller 78 upon the surface of the cam 21'.

The lever 31 has a downwardly directed handle portion 81, part of which is broken away in Fig. 1, to facilitate manual operation of both of the fingers 18-30 to manually actuate the fingers 75 within the limits of the pin and slot construc-

tion 27—28, and which operation may be effected without turning over the pulley 83 by hand or by operating the machine through an entire cycle of operation.

The guide plate 52 includes a front removable section 52', held in place by a knurled head screw 82, note Fig. 2, for gaining quick access to the tack guide channel in the event of any jamming, by reason of the structure of the tack delivery station, the delivery chute 51, delivery element 55 and slide 48, including the finger 30, become readily accessible.

The general structure of the frame 12 can be understood from a consideration of Figs. 1 and 2 of the drawings, taken with the showing in Fig. 4. It will appear from Fig. 4, that the finger 18 is beneath the setting plunger mechanism 15, at an angle, to deliver the button fastener devices directly above and in alignment with the positioned tack devices 34.

In Fig. 1 of the drawing, I have indicated in dot and dash lines part of the drive for the shaft 21, for example 83 shows in part a pulley driven from a belt 84, from a motor shaft, not shown. At 85 is indicated a chain and sprocket drive, from the shaft 21 to a shaft 86, from which there is a belt or other drive to the hoppers and other mechanism of the machine. No further description of this mechanism will be made, as it forms no part of the present invention.

In Fig. 1, I have shown the levers 25 and 26 in a full line position where the fingers 18 and 30 are fully advanced, and in dot and dash lines, I have shown, in part, the position of the levers 25 and 26 when the fingers are fully retracted.

In the operation of the machine the crank 22 operates the main lever 14 through the link 23 to actuate the plunger or other setting mechanism 15 to set or secure the fastener parts upon a suitable support. Operating off of the main lever 14 is the link 32 which in turn operates the levers 25 and 37. In more detail the link 32 is connected directly to the arm 26 which is a part of the articulate bell crank lever 25—26. In the normal operation of the machine the articulate levers 25 and 26 will remain in the same relative position to each other, while pivoting around the shaft 21 with the pin 27 carried by the lever 26 normally engaged in the left end of slot 28 in lever 25 by reason of the tension spring 29. The lower extension 35 of the lever 25 in turn actuates the lever 37 through the link 36. Movement of the levers 25 and 37 result in the forward and backward movements contributed to the fingers 18 and 30. If perchance one or both of the feed fingers 18 and 30 should jam during their respective feeding operations, by reason of the particular connection between levers 25 and 26 as explained above, the connected link 32 and lever 26 can continue through with their stroke while the lever 25 and 37 will remain at rest resulting in no damage to the motion. When the setting or securing mechanism 15 is in the raised position, the fingers 18 and 30 are in their fully advanced position, shown in full lines in Fig. 1. Conversely, when the mechanism 15 is in its lowermost position, having completed the attachment of the fastener devices to the support, the levers 25, 26 and 37 assume the dot-dash position illustrated in Fig. 1, the pivot of the link 36 with the arm 35, as at 81, having moved to the position indicated in dot-dash lines, whereas the pivot of the link 36 with the lever 37, as at 88, having also moved to the dot-dash position shown in said figure,

part of the lever 37 also being indicated in its dot-dash position. It will thus be seen that the throw or movement of the finger 18 is relatively slight as compared with the movement of the finger 30. In these dot-dash positions, the two fingers are now in a position ready to pick-up and deliver other fastening devices to the fixing or securing station as the mechanism 15 is again raised and returned to the full line position of Fig. 1, which completes a cycle of operation of the machine.

From the foregoing, it will be apparent that the entire operation of the machine is a quiet link and lever operation dispensing with all pounding that is occasioned by the use of cams and cam followers, and the motion or drive is a constant crank drive which is a smooth positive action, thus machines of the type and kind will operate very quietly and yet positively, means being provided to adjust feed of the two fingers to maintain the proper and desired relative alignment of the fastening devices in the machine. Further the free and independent movement compensates for improper functioning of the fingers and prevents jamming or destruction to the machine, this result being accomplished without interfering with the otherwise positive functioning of other machine parts.

By tying up the operation of the element 55 with the actuation of the slide 48, a positive and more or less foolproof delivery of tack elements in front of the finger 30 is assured. If for any reason the tack transfer element 55 should become accidentally jammed and fail to deliver a tack into proper position, or if perchance either one of the fastener elements should become jammed anywhere between the ends of their respective feed track to their setting station, then both feed fingers 18, 30 would be checked from further movement through the articulate construction of the bell crank lever 25, 26 and the ability of the lever 26 to continue to move relative to lever 25 against the influence of the spring 29. By this construction the other mechanism of the machine can complete its cycle of operations without danger of breaking the machine, after which the jammed fastener element can be removed or the jammed mechanism corrected.

For purposes of illustration, the machine has been illustrated as used in the delivery of specific types of fastener devices to the securing or coupling stations. It will be apparent, however, that other types and kinds of devices may be similarly delivered, the parts of the machine being constructed to suit the difference in structure of the devices employed.

Having fully described my invention, what I claim as new and desire to secure by Letters Patent is:

1. In a fastener setting machine, a pair of fingers, each finger being adapted to deliver a fastener element to predetermined position in the machine, a drive shaft, a crank actuated by said shaft and operating a main lever pivoted in the machine, said main lever actuating fastener setting mechanism of the machine, a lever for actuating each of said fingers, means adjusting said finger levers to control starting and ending position thereof, a supplemental lever having a link coupling with said first named main lever, and a lost motion connection between the supplemental lever and one of said finger levers.

2. In a fastener setting machine, a pair of fingers, each finger being adapted to deliver a fastener element to predetermined position in

the machine, a drive shaft, a crank actuated by said shaft and operating a main lever pivoted in the machine, said main lever actuating fastener setting mechanism of the machine, a lever for actuating each of said fingers, means adjusting said finger levers to control starting and ending position thereof, a supplemental lever having a link coupling with said first named main lever, a lost motion connection between the supplemental lever and one of said finger levers, and a spring coupling the supplemental lever with one of said finger levers maintaining said connection in drive position.

3. In a fastener setting machine, a pair of fingers, each finger being adapted to deliver a fastener element to predetermined position in the machine, a drive shaft, a crank actuated by said shaft and operating a main lever pivoted in the machine, said main lever actuating fastener setting mechanism of the machine, a lever for actuating each of said fingers, means adjusting said finger levers to control starting and ending position thereof, a supplemental lever having a link coupling with said first named main lever, a lost motion connection between the supplemental lever and one of said finger levers, a spring coupling the supplemental lever with one of said finger levers for maintaining said connection in drive position, and one of said finger levers having a hand grip portion facilitating manual operation thereof.

4. In fastener setting machines employing a pair of fastener delivery fingers with means for guiding said fingers in the machine to deliver fasteners to aligned position at a setting station of the machine, a pair of levers pivotally coupled at one end with the respective fingers, said levers being extensions at the other ends thereof, means adjustably coupling said extensions whereby actuation of one lever is transmitted to the other lever, a supplemental lever yieldably coupled with one of the first named levers, and means for imparting a positive reciprocating motion to the supplemental lever in actuating the finger levers in the feed of said fingers back and forth in the machine.

5. In fastener setting machines employing a pair of fastener delivery fingers with means for guiding said fingers in the machine to deliver fasteners to aligned position at a setting station of the machine, a pair of levers pivotally coupled at one end with the respective fingers, said levers having extensions at the other ends thereof, means adjustably coupling said extensions whereby actuation of one lever is transmitted to the other lever, a supplemental lever yieldably coupled with one of the first named levers, means for imparting a positive reciprocating motion to the supplemental lever in actuating the finger levers in the feed of said fingers back and forth in the machine, and means providing free movement of said finger levers with respect to the supplemental lever through said yieldable coupling.

6. In fastener setting machines employing a pair of fastener delivery fingers with means for guiding said fingers in the machine to deliver fasteners to aligned position at a setting station of the machine, a pair of levers pivotally coupled at one end with the respective fingers, said levers having extensions at the other ends thereof, means adjustably coupling said extensions whereby actuation of one lever is transmitted to the other lever, a supplemental lever yieldably coupled with one of the first named levers, means for imparting a positive reciprocating motion to the

supplemental lever in actuating the finger levers in the feed of said fingers back and forth in the machine, means providing free movement of said finger levers with respect to the supplemental lever through said yieldable coupling, one of said fingers comprising a slide operating in a guide tract, and the front end of said slide being adapted to engage a fastener in said guide track in delivery of said fastener to the setting station.

7. In fastener setting machines employing a pair of fastener delivery fingers with means for guiding said fingers in the machine to deliver fasteners to aligned position at a setting station of the machine, a pair of levers pivotally coupled at one end with the respective fingers, said levers having extensions at the other ends thereof, means adjustably coupling said extensions whereby actuation of one lever is transmitted to the other lever, a supplemental lever yieldably coupled with one of the first named levers, means for imparting a positive reciprocating motion to the supplemental lever in actuating the finger levers in the feed of said fingers back and forth in the machine, means providing free movement of said finger levers with respect to the supplemental lever through said yieldable coupling, one of said fingers comprising a slide operating in a guide tract, means comprising a chute for delivering fasteners one at a time into position in the guide track for engagement by the front end of said slide in delivery of fasteners to the setting station.

8. In a fastener setting machine having a pair of chutes for delivering independent fastener elements to pick-up position in the machine, a delivery finger for each chute, each finger having a lever for actuating the same, means adjustably coupling said levers whereby actuation of one lever will simultaneously operate the other lever, a drive lever for operating one of said levers, and means for actuating the drive lever for imparting back and forth movement to said fingers in delivery of fasteners from the chutes to a setting station in the machine.

9. In a fastener setting machine having a pair of chutes for delivering independent fastener elements to pick-up position in the machine, a delivery finger for each chute, each finger having a lever for actuating the same, means adjustably coupling said levers whereby actuation of one lever will simultaneously operate the other lever, a drive lever for operating one of said levers, means for actuating the drive lever for imparting back and forth movement to said fingers in delivery of fasteners from the chutes to a setting station in the machine, and said drive lever having a free coupling with the lever driven thereby, whereby both of said finger levers are free to move independent of the drive lever within predetermined limits.

10. In a fastener setting machine having a pair of chutes for delivering independent fastener elements to pick-up position in the machine, a delivery finger for each chute, each finger having a lever for actuating the same, means adjustably coupling said levers whereby actuation of one lever will simultaneously operate the other lever, a drive lever for operating one of said levers, means for actuating the drive lever for imparting back and forth movement to said fingers in delivery of fasteners from the chutes to a setting station in the machine, said drive lever having a free coupling with the lever driven thereby, whereby both of said finger levers are free to move independent of the drive lever

within predetermined limits, and a spring normally maintaining the drive and driven levers in predetermined relationship to each other.

11. In machines employing a pair of slides, a lever having a swivel coupling with each slide, means coupling said levers whereby movement of one lever is transmitted to the associate lever through said coupling means, and means comprising a third lever having a yielding coupling with one of the first named levers for actuating said first named levers to impart back and forth movement to said slides.

12. In machines employing a pair of slides, a lever coupled with each slide, means coupling said levers whereby movement of one lever is transmitted to the associate lever through said coupling, means comprising a third lever having a yielding coupling with one of the first named levers for actuating said first named levers to impart back and forth movement to said slides, and said yielding coupling permitting independently moving the first named levers a predetermined distance with respect to said drive lever.

13. In machines employing a pair of slides, a lever coupled with each slide, means coupling said levers whereby movement of one lever is transmitted to the associate lever through said coupling, means comprising a third lever having a yielding coupling with one of the first named levers for actuating said first named levers to impart back and forth movement to said slides, said yielding coupling permitting independently moving the first named levers a predetermined distance with respect to said drive lever, and means adjusting the stroke of the slides in the machine and with respect to each other.

14. In machines employing a pair of slides, a lever coupled with each slide, means coupling said levers whereby movement of one lever is transmitted to the associate lever through said coupling, means comprising a third lever having a yielding coupling with one of the first named levers for actuating said first named levers to impart back and forth movement to said slides, said yielding coupling permitting independently moving the first named levers a predetermined distance with respect to said drive lever, means adjusting the stroke of the slides in the machine and with respect to each other, and the coupling between said levers being such as to vary the forward and rear end point of travel of one slide with respect to the other slide.

15. In a fastener setting machine employing a fastener delivery slide for delivering fasteners to a setting station in the machine, said slide having an elongated guide track, means for delivering aligned fasteners laterally to one side of said track, an element operating in said track for picking-up and delivering fasteners one at a time to a position in the track for engagement by said slide, and said element having means engaged by the slide for moving the element into fastener delivery position.

16. In a fastener setting machine employing a fastener delivery slide for delivering fasteners to a setting station in the machine, said slide having an elongated guide track, means for delivering aligned fasteners laterally to one side of said track, an element operating in said track for picking-up and delivering fasteners one at a time to a position in the track for engagement by said slide, said element having means engaged by the slide for moving the element into fastener delivery position, and a spring for returning the element to position to pick-up a next successive fastener.

17. In a fastener setting machine employing a fastener delivery slide for delivering fasteners to a setting station in the machine, said slide having an elongated guide track, means for delivering aligned fasteners laterally to one side of said track, an element operating in said track for picking-up and delivering fasteners one at a time to a position in the track for engagement by said slide, said element having means engaged by the slide for moving the element into fastener delivery position, a spring for returning the element to position to pick-up a next successive fastener, and said element having means supporting aligned fasteners in said side delivery means when the element is in the first named or delivery position.

18. In fastener setting machines, a fastener delivery chute, a swinging element at the discharge end of the chute, a fastener feed finger slidably mounted in the machine adjacent the discharge end of the chute, a guide channel for said finger, said element being actuated by the finger to deliver a fastener from said chute into the channel forwardly of said finger as the finger is advanced in the channel, and said element having means supporting fasteners in the chute when said element is moved into delivery position.

19. In machines employing a pair of slides, a lever for actuating each slide, means coupling said levers, whereby movement of one lever is transmitted to the associate lever through said coupling means, and means comprising a third lever having a yieldable coupling with one of the first named levers for actuating said first named levers to impart back and forth movement to said slides.
